UNITED STATES PATENT OFFICE.

WILLIAM H. BILLING, OF EAST SAGINAW, MICHIGAN, ASSIGNOR OF TWO-THIRDS TO ARTHUR CAILLE AND EDWARD A. OWEN, OF SAME PLACE.

CASH-CARRIER.

SPECIFICATION forming part of Letters Patent No. 404,887, dated June 11, 1889.

Application filed December 22, 1888. Serial No. 294,420. (No model.)

To all whom it may concern:

Be it known that I, WILLIAM H. BILLING, a citizen of the United States, residing at East Saginaw, county of Saginaw, State of Michigan, have invented a certain new and useful Improvement in a Cash and Parcel Carrier; and I declare the following to be a full, clear, and exact description of the invention, such as will enable others skilled in the art to 10 which it pertains to make and use the same, reference being had to the accompanying drawings, which form a part of this specification.

My invention has for its object the provision of a novel and at the same time simple and effective means for the projection of a cash or parcel carrier car which travels over a taut wire. This I accomplish by means of the construction and combination of devices 20 hereinafter described and claimed.

In the drawings, Figure 1 is a side elevation of an apparatus embodying my invention. Fig. 2 is a sectional view through the bed-plate of the carriage, showing the spring 25 in its normal position. Fig. 3 is an end elevation of the same. Fig. 4 is a detail view of the plunger-block. Fig. 5 is a cross-section of the bed-plate. Fig. 6 shows a variation of the cash or parcel receptacle.

30 In the above drawings, A represents the usual hanger depending from the ceiling, and B the taut wire on which the car is adapted to travel.

C represents the bed-plate, C' the wheels, 35 and C² the detachable cup, of a cash-carrier car.

D is a cylinder located in the bed-plate of the car immediately under the wire and having its lower surface open or slotted, as shown 40 at d.

D' is a coil-spring located in the cylinder, and D² D³ are abutment-blocks adapted to slide freely in the cylinder and against which the ends of the coil-spring rest.

45 E is an arm rigidly attached to the standard and extending horizontally therefrom, and e is a pulley located on the outer end of the arm E.

F is a spring connected to the standard 50 above the wire, and F' is a cord or strap connected to this spring. The cord F' passes

down and under the pulley f, through the standard, and out above the arm E, over the pulley e, then back underneath the said arm and over the pulley f'. At its end it is provided with a suitable handle F².

G is what may be termed a "plunger-block." It is so shaped and provided with the orifice g that it will loosely embrace the arm E and travel thereon. Above the orifice g it is provided with a smaller orifice g', through which the cord F' may be passed, and the block may be rigidly engaged to this cord by the set-screw g². Extending from the upper side of the block G above the orifice g' is a projection 65 g³, adapted to extend up into the cylinder in the bed-plate of the car through the slot d.

H is a trigger fulcrumed to the standard just above where the wire B is engaged. This trigger is provided with the beveled shoulder 70 h, which is adapted to engage with the beveled shoulder c on the bed-plate of the car.

h' is a spring, one end of which is attached to the standard and the other to the end h² of the trigger. This spring is adapted to keep 75 the trigger in such a position that it will at any time engage with the car.

F³ is an adjustable nut or shoulder located on the cord or strap F' and adapted, when the latter is pulled, to release the trigger. 80

The operation of the device will now be understood. The car is at rest engaged by the trigger H. The operator, grasping the handle F², pulls the cord or strap. This causes the plunger-block G to slide forward, the projection g³ entering the slot in the cylinder in the bed-plate of the car. Here it comes in contact with the abutment-block D² and moves the latter forward, thus compressing the spring D' in the cylinder. The nut or shoulder F³, which has been correctly adjusted on the cord or strap, will, when the spring D' has been sufficiently compressed, strike the end h² of the trigger H, and thus release the car, when the resiliency of the 95 spring will serve to propel the car forward to the other end of the wire, where it is received and engaged by a similar device. Of course the shape of the arm E may be varied; but I prefer to make it square in cross-section, since 100 the plunger-block will then be kept in an upright position and be enabled to slide freely.

So, also, my invention would contemplate a variation of the means for releasing the trigger, and the mere location of these parts is of course optional.

5 Of course, if desired, a basket or other receptacle may be suspended from the bed-plate, and the detachable cup may or may not be attached thereto.

What I claim is—

- 10 1. In a cash and parcel carrier, the combination, with the taut wire, the hanger having an arm extending at right angles from the same and provided with pulleys, and a cord or strap passing over said pulleys and carrying a plunger-block, of a car adapted to travel on said wire and provided with a slotted cylinder, a coil-spring located in said cylinder and adapted to be compressed by the plunger-block entering the cylinder through the slot 15 therein, means for holding the car at the sta-
- 20

tion until the spring has been compressed, and means for releasing the car after the spring has been compressed, substantially as described.

2. In a cash and parcel carrier, the combination of the hanger A, having an arm E, provided with pulleys, the taut wire B, a car adapted to travel on said wire and provided with a slotted cylinder D, having a coil-spring D', and slides D² D³, located therein, the cord 30 F', having plunger-block G and nut F³ attached thereto, and the trigger H, substantially as described.

In testimony whereof I sign this specification in the presence of two witnesses.

WILLIAM H. BILLING.

Witnesses:

GEORGE GRANT,
E. J. DEMOREST.
